CLAIM

The ornamental design for a bench, as shown and described.

DESCRIPTION

FIG. 1 is a front perspective view of a bench embodying the present design;

FIG. 2 is a rear perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The bench is shown as broken in the center in FIGS. 1-2 and 5-9 to indicate that the claimed bench design is of variable length.
